UNITED STATES PATENT OFFICE.

EDMUND SCHNABEL, OF NEW YORK, N. Y.

DESIGN FOR A PIANO-CASE.

SPECIFICATION forming part of Design No. 32,113, dated January 16, 1900.

Application filed November 4, 1899. Serial No. 735,834. Term of patent 7 years.

To all whom it may concern:

Be it known that I, EDMUND SCHNABEL, a citizen of the United States, residing in the borough of Bronx, in the city and State of New York, have invented and produced a new and original Design for Piano-Cases, of which the following is a specification, reference being had to the accompanying drawing, forming part hereof.

Referring to the drawing, which is a perspective view of an upright-piano case embodying my design, the leading or material feature of the design is a central recess, concavity, or bay in the front of the case, with

plane portions on either side thereof, the said recessed portion of the front being curved backwardly from the side portions of the front.

Having thus described my invention, what I claim, and desire to secure by Letters Patent, is—

The design for a piano-case as herein shown and described.

EDMUND SCHNABEL.
